CLAIM

The ornamental design for a double door merchandiser, as shown and described.

DESCRIPTION

FIG. 1 is a perspective view of a double door merchandiser front with a broken line showing of handles for illustrative purposes only and forming no part of the claimed design showing my new design;

FIG. 2 is a front elevational view of FIG. 1;

FIG. 3 is a top plan view of FIG. 1;

FIG. 4 is a left side elevational view of FIG. 1;

FIG. 5 is a right side elevational view of FIG. 1;

FIG. 6 is a rear elevational view of FIG. 1;

FIG. 7 is a bottom plan view of FIG. 1; and,

FIG. 8 is an enlarged fragmentary perspective view of the door corners in the center showing the overhang.
